DICTATING MACHINE

Gerhard Dietrich, Nuremberg, Germany, assignor to
Grundig E.M.V. Elektro-Mechanische-Versuchs-Anstalt
Max Grundig, Furth, Germany

Filed June 21, 1973, Ser. No. 372,408

Term of patent 14 years

Int. Cl. D14—01

U.S. Cl. D26—14 B

FIG. 1

FIG. 2

FIG. 3

FIG. 4

FIG. 5

FIG. 6

FIG. 1 is a perspective view of a dictating machine showing my new design;

FIG. 2 is a top plan view of the dictating machine shown in FIG. 1;

FIG. 3 is a front view of the dictating machine shown in FIG. 1;

FIG. 4 is a side view of the dictating machine shown in FIG. 1;

FIG. 5 is a rear view of the dictating machine shown in FIG. 1; and

FIG. 6 is a bottom plan view of the dictating machine shown in FIG. 1.

The appearance of the side of the dictating machine not shown in the drawing is identical with the appearance of the side shown in FIG. 4.

I claim:

The ornamental design for a dictating machine, substantially as shown and described.
